UNITED STATES PATENT OFFICE.

RAYMOND R. SHAPLEY, OF HARRISBURG, PENNSYLVANIA, ASSIGNOR OF ONE-HALF
TO BENJAMIN FRANK SNAVELY, OF HARRISBURG, PENNSYLVANIA.

GAGE-COCK.

950,351.

Specification of Letters Patent. Patented Feb. 22, 1910.

Application filed August 2, 1909. Serial No. 510,788.

To all whom it may concern:

Be it known that I, RAYMOND R. SHAPLEY, a citizen of the United States, residing at Harrisburg, in the county of Dauphin and State of Pennsylvania, have invented a new and useful Gage-Cock, of which the following is a specification.

This invention relates to gage cocks, in which an auxiliary valve is provided for shutting off steam to the cock in an emergency, as when the main valve leaks.

Another object is to provide a main valve which may be readily removed when it leaks, or becomes otherwise defective, such removal being effected without blowing the pressure from the boiler.

The invention also has for its object to provide means for rotating or grinding the auxiliary valve on its seat to remove incrustations and corrosion.

A still further object is to provide a gage cock which is self-cleaning, and in which clogging up or stoppage is positively prevented.

With these objects in view, the invention consists in a novel construction and arrangement of parts to be hereinafter described and claimed, reference being had to the drawing hereto annexed, in which,—

Figure 1 is a longitudinal sectional view of the cock. Fig. 2 is a transverse section on the line 2—2 of Fig. 1, and; Fig. 3 is a transverse section on the line 3—3 of Fig. 1.

Referring to the drawing, 5 denotes the body of the cock, on the inside of which are main and auxiliary valve seats 6 and 7, respectively. The body is open at both ends, and has at one end a screw threaded portion 8, which screws into the boiler wall.

The valve seat 7 is next to the boiler, and engageable with said seat is a valve 9, which is in the shape of a plug, having one of its ends beveled to fit snugly on the seat, and provided at its opposite end with guide wings 10, which work in the bore of the body 5. When this valve is off its seat, steam flows past the valve seat by the way of the spaces between the wings. A pin 12, extending across the bore of the portion 8 prevents the valve from working out when there is no pressure in the boiler. The valve 9 is exposed to the pressure in the boiler, which causes it to seat as hereinafter described.

The seat 6 is engaged by the main valve 13, which is a plug having one of its ends

beveled to fit said seat. From this end of a valve projects a stem 14, which is adapted to enter a hole 15, made in the valve 9, for a purpose to be presently described. The stem is angular in cross section, and the hole is shaped accordingly. From the opposite end of the valve 13 projects a stem 16, which enters an angular opening made in the valve stem 17, a cross pin 18 passing through said parts, connecting the same rigidly together, so that the valve 13 may rotate with the stem 17. The valve is therefore separably connected to the valve stem, and can be removed when it leaks, or becomes otherwise defective. The valve stem 17 has a screw-threaded portion 19, which engages threads in the bore of the body 5. The valve stem extends through a packing nut 20 to the outside of said body, and is fitted with a knob or handle 21. Intermediate its ends the body 5 is fitted with a discharge nozzle 22.

The valves 9 and 13 move to their respective seats in opposite directions, and the length of the stem 14 is such that when the main valve 13 is screwed down to its seat, said stem may enter the hole 15, and when the stem reaches the inner end of said hole, the valve is pushed off its seat, this movement taking place before the main valve 13 seats, so that the discharge of steam or water from the cock may take place.

The auxiliary valve is to remain off its seat at all times, except when the main valve leaks, and it is desired to repair the same. To close the auxiliary valve, the stem 17 is unscrewed to withdraw the stem 14 from the auxiliary valve sufficiently to permit said valve to be seated by the boiler pressure. If the auxiliary valve is corroded or incrusted the valve stem is unscrewed until the stem 14 is off the inner end of the hole 15. The valve stem is then turned alternately to the right and left, which will impart the same movement to the auxiliary valve, whereby it is ground on its seat. The pressure now being shut off from the boiler, the main valve may be safely removed for renewal or repair, and its seat may also be repaired.

Between the valve seats 6 and 7, the body 5 has a contracted passage 23, through which the stem 14 extends, the corners of said stem being in engagement with the wall of said passage. Said stem is thus made

5
to serve as a scraper for removing all sediment or incrustations tending to accumulate in the passage. This scraping action occurs every time the cock is opened and closed, which makes the same self-cleaning.

What is claimed is:—

1. A gage cock comprising a body having a pair of valve seats, and a contracted passage therebetween, valves engageable with 10 said seats, one of said valves being exposed to the boiler pressure, means for operating the other valve, and a stem on said valve engageable with the first mentioned valve for unseating the same, said stem being polygonal in cross section and extending through 15 the contracted passage, and engageable at its corners with the wall thereof.

2. A gage cock comprising a body having a pair of valve seats, and a passage therebetween, valves engageable with said seats, one 20 of said valves being exposed to the boiler pressure, means for operating the other valve, and a stem on said valve engageable with the first-mentioned valve for unseating the same, said stem extending through the 25 aforesaid passage, and having scraping edges engageable with the wall thereof.

In testimony that I claim the foregoing as my own, I have hereto affixed by signature in the presence of two witnesses.

RAYMOND R. SHAPLEY.
